UNITED STATES PATENT OFFICE.

LEE ROY ARTHUR, OF GLEN'S FALLS, NEW YORK, ASSIGNOR OF ONE-HALF
TO JOSEPH FOWLER, OF SAME PLACE.

SACK-TURNER.

SPECIFICATION forming part of Letters Patent No. 287,214, dated October 23, 1883.

Application filed February 5, 1883. (No model.)

To all whom it may concern:

Be it known that I, LEE ROY ARTHUR, of Glen's Falls, in the county of Warren and State of New York, have invented a new and 5 Improved Sack-Turner, of which the following is a full, clear, and exact description.

My invention consists of a simple contrivance for turning small sacks, as the fingers of gloves and other like articles of leather or 10 cloth that are required to be turned after being sewed up, to turn the seams inside.

Reference is to be had to the accompanying drawings, forming part of this specification, in which similar letters of reference indicate 15 corresponding parts in all the figures.

Figure 1 is a side elevation of my improved sack-turner. Fig. 2 is a front elevation showing the sack placed on the first finger, preparatory to being turned; and Fig. 3 is a front 20 elevation showing the sack shifted onto the other finger and turned.

On any suitable block or bar of wood or other material, *a*, suitable for being held in the hands or in a vise, and having projections *b* at each end, 25 I fix a finger or bar, *c*, by a pivot, *d*, upon one of the projections *b*, and a stop, *e*, to limit the swing of said finger in one direction, and on the other projection *b*, I fix a stationary finger, *f*, the two fingers being so that they will touch 30 each other at the ends, or nearly so, when finger *c* is shifted into line with *f*, and by preference I groove the end of *c* a little, so that the end of finger *f* may project a little into the groove, but that is not very essential. I 35 prefer to make the finger *f* to conform in shape to the shape of the sack to be filled, when turned, and, if desired, both of the fingers may be so shaped.

The dotted lines *g*, Fig. 2, represent the 40 sack to be turned placed on finger *c*, said finger being swung out of line a little on its pivot

d, to receive the sack, preparatory to being shifted in line with finger *f* with the sack on it. The dotted lines *h*, Fig. 3, represent the sack on finger *f*, after being turned, onto which the 45 sack is shifted by the act of turning it, which consists in placing the fingers under the lower end of the sack, while on fingers *c*, and stripping it upward onto *f*, while the end of the sack is held between the ends of the two fingers, all of which will be clearly understood by circumspection of the drawings. Different 50 forms and sizes of fingers will be used for different articles, and the fingers may be detachably connected to the block for changing them 55 when required.

The stop *e* may be dispensed with, and any equivalent of the block *a b* may be employed, as two blocks, *b*, attached to a table or bench.

Having thus fully described my invention, I 60 claim as new and desire to secure by Letters Patent—

1. The improved sack-turner, consisting of block *a b*, or its equivalent device, pivoted finger *c*, and stationary finger *f*, combined and 65 arranged substantially as described.

2. The improved sack-turner, consisting of block *a b*, or its equivalent device, pivoted finger *c*, stop *e*, and the stationary finger *f*, combined and arranged substantially as de- 70 scribed.

3. The improved sack-turner, consisting of block *a b*, or its equivalent device, pivoted finger *c*, and stationary finger *f*, one of said fingers being grooved on the point and receiv- 75 ing the point of the other finger in its groove, substantially as described.

LEE ROY ARTHUR.
